US00D592703S

(12) **United States Design Patent**
Graham

(10) **Patent No.:** **US D592,703 S**
(45) **Date of Patent:** **** May 19, 2009**

(54) **PENCIL SUPPORT**

(76) Inventor: **Timothy T. Graham**, 3798 Golden Meadow Rd., Asheboro, NC (US) 27205

(**) Term: **14 Years**

(21) Appl. No.: **29/312,958**

(22) Filed: **Nov. 25, 2008**

Related U.S. Application Data

(63) Continuation-in-part of application No. 29/273,628, filed on Mar. 9, 2007, now abandoned.

(51) **LOC (9) Cl.** **19-06**

(52) **U.S. Cl.** **D19/81**

(58) **Field of Classification Search** ..... D19/54-55, D19/65, 75, 77-78, 81, 84-85, 95, 99-100; 206/214; 248/316.7, 205.3, 65; 211/69.1, 211/69.9, 69; D8/70-71, 396; 24/11 CC

CLAIM

The ornamental design for a new, original and ornamental design for a pencil support, as shown and described.

DESCRIPTION

FIG. 1 is a top, front, left side reduced perspective view of a pencil support embodying my design;

FIG. 2 is a front elevational view thereof;

FIG. 3 is a rear elevational view thereof;

FIG. 4 is a left side elevational view thereof, the right side elevational view being a mirror image thereof;

FIG. 5 is a top plan view thereof;

FIG. 6 is a bottom plan view thereof;

FIG. 7 is a top, front, left side reduced perspective view of an alternate embodiment of my design;

FIG. 8 is a front elevational view thereof;

FIG. 9 is a rear elevational view thereof;

FIG. 10 is a left side elevational view thereof, the right side elevational view being a mirror image thereof;

FIG. 11 is a top plan view thereof; and,

FIG. 12 is a bottom plan view thereof.

The broken lines are for environmental purposes only and form no part of the claimed design.
